UNITED STATES PATENT OFFICE.

JOAQUIN JULIO DE LA ROZA, SR., OF BROOKLYN, NEW YORK, ASSIGNOR TO BAGASSE PRODUCTS CORPORATION, OF NEW YORK, N. Y., A CORPORATION OF NEW YORK.

ALCOHOL AND METHOD OF PRODUCING THE SAME.

No Drawing.

Application filed March 22, 1927. Serial No. 177,464.

This invention relates to alcohol and a method of producing the same. It has for an object to produce alcohol from burned sugar cane.

5 Another object consists in providing certain improvements in the steps followed, whereby the above named and other objects may effectively be attained.

It is well known that the sugar fields are 10 frequently subjected to fires which destroy a large amount of the crop. The action of the fire ordinarily is to consume all parts of the cane, except the stalk. This latter normally contains approximately seventy-five percent 15 of water so that it will usually resist the flames but, on standing, after the fire, there occurs, in the course of a very few days, a chemical inversion of the sucrose contents within the stalk, whereby there is formed dextrose, levulose, etc. This is commonly known 20 as turning or souring of the sugar cane, and takes place in from one or two to four or five days, according to weather conditions.

Because of this, it is necessary that the 25 stalks should be cut and treated in the sugar mill almost immediately after the fire, if the usual sugar product is to be obtained, because the soured or turned sucrose juices cannot be treated to produce the crystallized sugar 30 that is the usual product from sugar cane.

It is frequently impossible to cut the burned cane and have it used in the sugar mill within the few days period, so that the fact is that vast quantities of the burned cane are allowed 35 to rot in the fields, or are cut and either thrown away or used as an inefficient fertilizer. This constitutes a great economic loss to the planters, frequently involving bankruptcy; and it also occasions a great economic 40 loss, more broadly speaking, because a very abundant source of alcohol is thereby wasted.

I have found that the burned sugar cane, which has soured or turned, can easily be employed as a substantial and commercially advantageous source of alcohol, and my invention contemplates said product produced from the said material, and the method of producing the same, both of which, I believe, have heretofore been unknown.

50 In carrying out my process, I allow the burned sugar cane to stand under ordinary atmospheric conditions until there has been a substantial inversion or fermentation of the sucrose and other fermentable sugars con-

tained in the cane. This will generally 55 amount to from twelve to twenty percent of the total weight of the sugar cane.

After this condition has been reached, the sugar cane is cut and is ground in a mill in a manner very similar to the grinding of cane 60 for the purpose of producing sugar. I have found that, as a rule, the grinding of the burned cane in one set of three rollers will be sufficient; and that it is desirable to arrange the spacing and pressure of the rollers so that 65 no great crushing effect is applied to the cane. This sufficiently extracts the desired juices, while leaving the cellulose portion uninjured for treatment to obtain other products, as pointed out for instance in my copending applications, Serial Nos. 97,452 and 97,453, filed March 25, 1926.

The juices thus extracted are in an initial stage of fermentation, containing large quantities of bacteria capable of promoting further 75 fermentation, and should be put through the steps of complete fermentation and distilling generally employed in the production of alcohol from molasses and similar materials, and well understood in this art; with 80 the notable difference that, in carrying out my invention, the amount of yeast or other fermenting agent required will be a minimum, or the same may be omitted entirely.

In the souring, turning or fermentation of 85 the burned cane, various acids are engendered, so that it is desirable, in handling the juices, to employ apparatus which is resistant to acid. This is not only for the purpose of prolonging the useful life of the apparatus, 90 but also for preventing metallic particles of the apparatus acted upon by the acids from injuring the product. Unprotected iron apparatus or equipment would be particularly objectionable in this respect.

95 My invention takes note of the fact that burned sugar cane is more acid than unburned sugar cane, so that the former more readily adapts itself to the process of manufacturing alcohol. In other words, the condition 100 which has rendered sugar cane unfit for the manufacture of the usual sugar product, and has caused it to be practically discarded heretofore, is taken advantage of by my invention to promote the usefulness of the sugar cane as a source of alcohol production.

I have referred in the foregoing to the utilization of sugar cane which has been

burned without the intent of the owner there-
of but, it will be understood that, if desired,
a given amount of sugar cane could be pur-
5 posedly fired for the purpose of producing the
burned cane that is the valuable material
for the manufacture of alcohol in accordance
with this invention.

I desire it to be understood that various
changes may be resorted to in the steps fol-
10 lowed, and apparatus employed, without de-
parting from the spirit and scope of my in-
vention; and hence, I do not intend to be
limited to details except as they may be in-
cluded in the claim.

What I claim is:

A method of producing alcohol which com-
prises, extracting the liquid content from
burned green sugar cane which has been sub-
mitted to ordinary atmospheric conditions
existing in cane growing localities until an in-
15 version of sugar content has occurred, fer-
menting and distilling the said extracted con-
tent.

In testimony, that I claim the foregoing as
my invention, I have signed my name this 25
21st day of March, 1927.

JOAQUIN JULIO DE LA ROZA, SR.
